DESIGN FOR A GRAVE VAULT OR SIMILAR ARTICLE

Allen F. Beck, Columbus, Ohio

Application June 8, 1933. Serial No. 48,343

Term of patent 14 years

To all whom it may concern:

Be it known that I, ALLEN F. BECK, a citizen of the United States, residing at Columbus, in the county of Franklin and State of Ohio, have invented a new, original, and ornamental Design for a Grave Vault or Similar Article, of which the following is a specification, reference being had to the accompanying drawings, forming a part thereof.

Fig. 1 is a perspective view of a grave vault or similar article, showing my new design;

Fig. 2 is a vertical transverse sectional view taken on the plane indicated by the line 2—2 of Fig. 1;

Fig. 3 is a detail horizontal sectional view on the plane indicated by the line 3—3 of Fig. 1.

Fig. 4 is a detail longitudinal sectional view on the line 4—4 of Fig. 2.

I claim:

The ornamental design for a grave vault or similar article, as shown.

ALLEN F. BECK.
